UNITED STATES PATENT OFFICE

ARTHUR M. WICKWIRE, JR., OF NUTLEY, NEW JERSEY, ASSIGNOR OF ONE-HALF TO ANTHONY GUITEREEZ, OF PASSAIC, NEW JERSEY, AND ONE-HALF TO PEERLESS ROLL LEAF COMPANY, INCORPORATED, OF UNION CITY, NEW JERSEY, A CORPORATION OF NEW YORK

PRINTING OR STAMPING CELLULOSE TUBES AND OTHER ARTICLES

Application filed September 19, 1930. Serial No. 433,115.

The invention relates to machines for stamping and printing on articles requiring heavy impressions and particularly to machines adapted to handle peculiar articles 5 rapidly and efficiently.

The invention has for an object to provide an improved stamping machine in which the regularity and clear outline of the impression may be insured. To this end, in addition to improving the feed of roll printing material, it is an aim to present a novel means to secure a rotating platen disc or dial plate and the die rigidly in position and in a mutual fixed relation during the making of the impression, there having been difficulty heretofore in a machine of this character from instability. It is a special aim to enable the locking of the platen very rigidly in stationary position during the making of an impression, notwithstanding that a rapid step-by-step dial movement of the platen is effected. In the stamping of articles to impress characters in metal leaf or pigment one of the most practical methods involves the use 15 of a heated die in a vertically reciprocating stamping head, and a dial plate moved step-by-step having article-holding means thereon so that the articles are brought into alignment successively with the die and held stationary while the die is pressed thereupon, a web-carrying the metal leaf, ink or pigment being fed between the die and article during the clearance of the die. During the impression the heating of the web causes a 20 softening of the printing material, so that if there is any slight tendency of the platen to move horizontally relatively to the die, while the heated web is initially engaging the article, such movement will not be opposed, and a blurring of the impression will result. A Geneva gear intermittent action has been 25 used in the movement of the dial plate, but it has not been found practicable to so construct this as to insure absolutely against such defect, and it is an important attainment of my invention that the objection referred to is overcome.

It is an important purpose to coordinate the locking device peculiarly with the stamping head action.

Additional objects, advantages and features of invention will be found in the construction, arrangement and combination of parts, as involved in the embodiment of the invention, and understood from the following description and accompanying drawings, wherein,

Figure 1 is a side view of the machine.

Figure 2 is a fragmentary top view of the dial plate and locking cam.

Figure 3 is a fragmentary cross section on the line 3—3 of Figure 1.

Figure 4 is a front view of the device.

Fig. 5 is a fragmentary side view from the left of Fig. 4.

Fig. 6 is a view of the face of the friction disk.

There is illustrated a stamping machine comprising a pedestal 10, on which there is mounted a dial plate or work holder 11, rotatable and moved step-by-step by means of Geneva gear (not illustrated) or other intermittent action, so coordinated with the stamping head 12 that during the interval of inertia of the plate 11 the head 12 may move down and engage the work on the plate. The mechanism (not illustrated) for operating the head is mounted in the case 13, which is formed as an upward extension of the pedestal. The stamping mechanism is so constructed in a familiar way as to be operated at will by depression of the foot pedal 14 shown, the operating and pedal control mechanism not being illustrated here. The plate 11 customarily rotates continuously step by step independently of the pedal. The dial plate or work holder consists of a circular planiform plate laid revolvably upon a table plate 15 through which there extends a spindle 16 upon which the dial plate is fixed removably.

Upon the top of the dial plate there are provided a plurality of pairs of guide plates 17 arranged each pair in parallel relation and secured upon the plate 11 in adjustable spaced relation. Radial channels 18 are thus formed between the plates 17 in which there may be laid or inserted the articles whereby they are stamped, to be carried to position and held while the stamping head operates.

thereon, then moved clear of the stamping head while the following article is moved into position for stamping. The opposed edges of the plates 17 are undercut or rabbeted to better retain the articles. This step by step movement is in a counter clockwise direction, as viewed from above, so that the stamped articles, on the second stage of movement after stamping are brought to the position indicated at A, in Figures 3, 4 and 5.

At the head of each channel 18 on the dial plate there is a cross plate 29, forming the head of the channel, and on this there is mounted a spring clip 30 extending a short distance over the channel, inclined downwardly to engage yieldingly on the bottom of the channel, its extremity curved upwardly so that an article to be stamped may be readily slipped under the clip to be frictionally held.

The stamping head may be of a usual construction, but as illustrated includes a vertically reciprocable poll 20 mounted on the case 13 in a familiar way. On this poll a die 25 chase 21 is removably secured, the details of this chase being old. Secured to the poll there is a substantially U-shaped frame 22 including front and rear side members 23, connected integrally at the left hand side of 30 the machine. At the left an arm 24 on this frame is projected diagonally outward and upward, upon which there is mounted a stock roll 25 of a color carrying or metal leaf-carrying web 26, which is fed beneath the die. Between the front and rear side members 23 at the right hand side there are mounted two corrugated feed rolls, a large lower one 27 on a fixed bearing and an upper smaller one 28 spring pressed upon the first in an approved manner. The members 23 of the head frame 22 are also formed with vertical guide bearings 31 at left and right of the poll, and in these there are slidable rods 32 threaded at their upper ends and engaged in 45 knurled finger nuts 33 by which they are supported. Between each pair of rods there are revolvably mounted left and right clearing rolls 34 of very small diameter. Beneath these rolls passes the web 26, which is thus held clear of the die. The rods are provided with shoulders near their lower ends, and between these shoulders and the frame 22 there are confined springs 35 by which the rolls 34 are held at their lowermost positions, so as to hold the web clear of the die, but yieldable to engagement with the dial plate and parts thereon. In order that the rolls 34 shall not press the web upon the parts of the dial plate in such manner as to 55 soil the latter, or waste color or foil, the rods 32 are extended slightly below the rolls 34, so that when the stamping head is lowered to engage the work, the rods engage the dial plate or guide plates 17 and are raised, thereby permitting the web to be lifted into con-

tact with the face of the die, by reason of the slight rewinding effect of the take-up spring 36 to be described.

The stock roll is provided with a helical friction tension and take-up spring 36 acting in a peculiar manner to effect the desired functions of this spring. The spring is anchored at one end to a stud shaft 37 carried fixedly by the arm 24 before mentioned, by means of a collar 38 to which the end of the spring is permanently secured, and the collar is slideable on the shaft 37 and held in adjusted positions by means of a set screw 39. The collar and spring are introduced around the end of the shaft and the collar pressed inward so as to compress the spring against the drum 25, thereby pressing the latter against an adjustable flange collar 40 on the shaft 37.

The collar 40 is held in adjusted positions by a set screw engaging the shaft 37, so that the roll may be adjusted to align with the die. The end of the drum is formed with radial ribs 41 on its outer side, next the spring, and these ribs may be V-shaped for the purpose to be explained. The end of the spring next the drum is formed with a bill portion to hook yieldingly upon the ribs so as to cause a winding of the spring a distance until a desired torsion is applied to the spring 36 when the bill will slip back one rib at a time as the web is unwound. When the rods 32 engage the dial plate, the slack thus caused is taken up by the reaction of the spring 36 winding the roll slightly until checked by the web becoming taut across the die. The shaft of the lower feed roll 27 is extended through the front side member of the frame 22 and provided with a grooved wheel 43 around which there is stretched a helical spring 44 resting in the groove, the ends of the spring being secured to the frame 22 so that it acts as a brake.

This shaft is also provided with a hand knob 45 by which the roll may be manually turned when necessary. The opposite end of this roll shaft is provided with a ratchet and pawl operating device including an oscillatable gear 46 revoluble on the shaft of the roll, and upon the gear there rests a rack bar 47, extending rearwardly and having its rear end pivoted adjustably on a depending rigid slotted arm 48 fixed on the case 13.

By adjustment of this pivot on the arm 48 the degree of feed of the web 26 may be determined. With the rack bar horizontal when the stamping head is at the upper limit of its movement the minimum extent of feed for each stamping operation is involved, and the higher the pivot is adjusted the greater the extent of the feed. A rack 49 holds the discharge end of the web outward of the dial plate so that it may drop clear of the machine. The dial plate is rotated by means of a Geneva movement similar to that shown at 8 in

the patent to Douglass, No. 1,026,790, which may be driven by the shaft 50, connected with the operating mechanism in the case 13. The periphery of the plate 11 is formed with V-shaped notches, the number of which is the same as the number of channels 18 and the notches are correspondingly spaced apart. A locking bar 55 is pivoted on the table plate 15 to the rear of the dial plate and is provided with a wedge shaped bill 56 adapted to enter one notch whenever the plate 11 is stopped by the Geneva movement. The bar 55 is held withdrawn by a spring 57, and is moved into engagement with the plate 11 by operation of the stamping head to make an impression. For this purpose, a depending arm 60 is mounted on the rear side of the rear member 23 of the frame 22, the lower end portion of which arm is formed with an inclined cam face 61 at the inner side, to wipe against the rear side of the bar 55 and press it toward the dial plate 11 as the stamping head descends. With the stamping head at the upper limit of its movement, the wiping face 61 extends beside the bar 55 a distance. The table plate 15 is suitably apertured to receive the arm 60 therethrough. It should be noted that the arm 60 is comparatively sturdy, but is narrowed midway of its length, for a distance, sufficiently to give it a measure of yieldability in case the arm 55 engages the plate 11 positively before the downward movement of the inclined face 61 on the bar 55 ceases. Indeed it is the purpose that the arm 60 shall so function, in order to insure positive locking of the plate 11, without liability of beginning of loose movement after slight wear of the engaging parts. The inclined face 61 is of less altitude than the vertical movement of the stamping head and terminates at a vertical inner side 63, which will be engaged with the back side of the bar 55 while an impression is made by the stamping head on articles carried by the dial plate.

15 A work holding and ejecting means at A is provided to remove articles from the channels 18 at the left hand side of the machine, and that mechanism forms the subject of my copending application of even date with this application, improvements in printing or stamping cellulose tubes and other articles, Serial No. 483,114.

20 In operation, the work is fed to the channels 18 by an operator or any approved means, the plate 11 rotating constantly step by step, through operation of the Geneva gear and cam. The stamping operation is ordinarily controlled by the foot pedal, depression of which causes the stamping head to operate.

25 As articles in the channels 18 begin to arrive under the stamping head, the pedal is operated, and is kept depressed as long as articles are brought to position. As the head descends, the arm 60 presses the locking bar 55 into engagement with the plate 11 to hold it in

secure registry with the die, the rods 32 engage the plate 11 permitting the web 26 to be lifted to the face of the die by take-up action of the roll 25 and the rack bar 47 is caused to draw the upper side of the gear 46 toward the left. The die now presses the web upon the work and rises, causing the rack bar 47 to move the gear 46 oppositely to its first movement, at which time the ratchet will operate to turn the roll 27 and pull the web further beneath the die against the action of the spring 36. The arm 60 is also disengaged from the bar 55, which is returned to disengaged position with respect to the plate 11, by the spring. The rods 32 press the rolls 34 downwardly to clear the web 26 from the die immediately after the impression, so that the web is freed to be fed beneath the die by the feed rolls 27-28, before the next stamping operation. The stamped article is moved from beneath the stamping head by the next step movement of the dial plate 11, a new article being brought into position by the succeeding channel 18 by the same movement that clears the stamped article. On the second step movement after stamping, the article lies beneath the ejector wheel 24 operation of which is described in my copending application before mentioned.

30 I claim:

1. In a stamping machine, a stamping head, means to operate the head, a table plate, a rotatable dial plate over the table plate, work holding members spaced about the dial plate, means to rotate the dial plate step by step to align the work holding members successively with the stamping head, said dial plate having peripheral V-shaped notches, in number and spacing corresponding to the work holders, a locking member mounted over the table plate removably to wedge in the notches successively coincidently with alignment of respective work holders with the stamping head, a cam member carried by the stamping head having an inclined face to engage the locking member and move the latter into locking engagement with the dial plate, and yielding means to move the locking member to disengaged position.

35 2. The structure of claim 1 in which an opening is formed through the table plate, and the cam member has a side parallel to the movement of the stamping head to engage the side of the opening during the operation of the stamping head.

40 3. A web feeding means for machines of the character described, comprising a frame carried by the stamping head having feed rolls mounted thereon outwardly of and above the die face of the head, a groove wheel fixed with respect to one roll, a helical spring laid in the groove and having its ends secured to the frame under tension to bear upon the grooved wheel as a brake.

45 4. The structure of claim 3 in which the

opposite end of the roll has a gear revoluble thereon, a ratchet and pawl connection between the gear and roll, a vertical anchorage, a rack bar meshed with the gear and adjustably pivoted on the anchorage adjustable vertically thereon.

5. In a machine of the character described, a stamping head, a stock roll mounting carried thereby including a shaft outwardly of 10 and above the die face of the head, a roll revoluble thereon, a thrust bearing for the roll adjustable on the shaft, a torsion and compression spring having one end secured and adjustable on the shaft and its other end in 15 pressing engagement with the roll opposite the thrust bearing, means to feed web from the roll beneath the die face of the head, the spring and roll engagement including means whereby rotation of the roll will be torsionally 20 resisted and stress of the spring will tend to rewind the roll, the engagement being yieldable to a predetermined excess torsional stress whereby slack produced in the web will be rewound by the spring, and the web kept 25 under tension.

6. The structure of the claim 5 in which circumferentially spaced irregularities are formed on the roll, the spring constructed to engage in the irregularities yieldingly, 30 whereby the engaged end of the spring will slip from one to another of the irregularities in succession when the torsion stress is sufficient to overcome the compression stress and friction on the spring end.

35 7. The structure of claim 5 including vertically movable spring pressed rolls at opposite sides of and slightly below the face of the die, means to limit their downward movement, and web feeding means, the web passing below the last mentioned rolls.

In testimony whereof I affix my signature.
ARTHUR M. WICKWIRE, JR.
